CLAIM

The ornamental design for a reconfigurable infant support structure, as shown and described.

DESCRIPTION

FIG. 1 is a top perspective view of a reconfigurable infant support structure according to the present invention; FIG. 2 is a top view of the reconfigurable infant support structure of FIG. 1;

FIG. 3 is a bottom view of the reconfigurable infant support structure of FIG. 1;

FIG. 4 is a front view of the reconfigurable infant support structure of FIG. 1;

FIG. 5 is a rear view of the reconfigurable infant support structure of FIG. 1;

FIG. 6 is a left side view of the reconfigurable infant support structure of FIG. 1; and,

FIG. 7 is a right side view of the reconfigurable infant support structure of FIG. 1.

The broken lines shown in the figures are included for the purpose of illustrating the unclaimed portions of the article and form no part of the claimed design.
